DESIGN FOR A TEXTILE FABRIC OR SIMILAR ARTICLE OF MANUFACTURE

William F. Cook, Brooklyn, N. Y., assignor to
The Pantasote Leather Company, Passaic, N. J., a corporation of New Jersey

Application November 2, 1935, Serial No. 59,339

Term of patent 14 years

To all whom it may concern:

Be it known that I, William F. Cook, a citizen of the United States of America, residing in the Borough of Brooklyn, county of Queens, city and State of New York, have invented a new, original, and ornamental Design for a Textile Fabric or Similar Article of Manufacture, of which the following is a specification, reference being had to the accompanying drawing, forming a part thereof, and showing a face view of a piece of textile fabric embodying my design.

The design is intended to be repeated on the textile fabric as shown.

I claim:

The ornamental design for a textile fabric or similar article of manufacture substantially as shown and described.

WILLIAM F. COOK.
